Ralph V. Burdick and Ralph V. Burdick, Jr., Loudonville,
N.Y. (both of Drawer 29, Albany, N.Y.)

Filed June 24, 1963, Ser. No. 75,479

Term of patent 14 years

(Cl. D58—11)

FIG. 1

FIG. 2

FIG. 3

FIG. 4

FIG. 5

FIG. 1 is a front elevational view of a shoe polish box showing our new design;

FIG. 2 is a rear elevational view thereof;

FIG. 3 is a top plan view thereof;

FIG. 4 is a bottom plan view thereof; and

FIG. 5 is an enlarged cross-sectional view thereof taken on line 5—5 of FIG. 3.

The dominant features of our design reside in the provision of the ribs in combination with the recessed finger guide on the raised top of the box all as shown.

We claim:

The ornamental design for a shoe polish box, as shown and described.
